UNITED STATES PATENT OFFICE

PHILIP J. KNORPP, OF WILMETTE, ILLINOIS

DESIGN FOR A CANDLE HOLDER

Application filed June 2, 1930. Serial No. 35,884. Term of patent 14 years.

To all whom it may concern:

Be it known that I, PHILIP J. KNORPP, citizen of the United States, residing at Wilmette, county of Cook, State of Illinois, have invented a new, original, and ornamental Design for a Candle Holder, fully described and represented in the following specification and the accompanying drawing, forming a part of the same, said drawing showing my new design as applied to a candle holder, the essential feature of which is the contour of the holder, Fig. 1 being a plan view of the holder, and Fig. 2 a section thereof on the line 2—2 of Fig. 1.

What I claim is:

The ornamental design for a candle holder as shown and described.

In testimony whereof I have hereunto set my hand.

PHILIP J. KNORPP.
